DESIGN FOR A COAT

Salvatore Lo Prete and Vincenzs Lo Prete, New York, N. Y.

Application May 11, 1937, Serial No. 69,296

Term of patent 3½ years

To all whom it may concern:

Be it known that we, Salvatore Lo Prete and Vincenzs Lo Prete, citizens of the United States of America, residing in New York, county of New York, and State of New York, have invented a new, original, and ornamental Design for a Coat, of which the following is a specification, reference being had to the accompanying drawing, forming part thereof, wherein,

The furred upper portion of the coat is an integral part of the coat, and a stationary portion thereof.

We claim:

The ornamental design for a coat, substantially as shown and described.

SALVATORE LO PRETE.
VINCENZS LO PRETE.
